UNITED STATES PATENT OFFICE

HERMON L. VAN VALKENBURG, OF WAUWATOSA, AND GEORGE W. HOFEM, OF MILWAUKEE, WISCONSIN, ASSIGNEES TO SQUARE D COMPANY, OF DETROIT, MICHIGAN

SWITCH

Application filed March 3, 1932. Serial No. 596,542.

This invention relates to switches, and is particularly directed to a push button type of switch.

Objects of this invention are to provide a novel form of push button switch provided with a switch closing button operating to close the switch mechanism, and with a release or opening button which releases the switch mechanism and allows the switch mechanism to open although the closing button may be held down, and to provide a plurality of overload devices either or both of which will trip the switch mechanism and, allow the switch to open, such action taking place whether or not the closing or starter button is held down at the time either or both of the overload devices operates, thereby adapting the switch to polyphase systems, such for example as supply motors or other polyphase loads.

Further objects of this invention are to provide a switch in which there is a trip-free mechanism provided which normally operatively connects the switch closing or starter button and the switch mechanism, but which nevertheless trips free of the starter button and allows the switch mechanism to open under predetermined conditions, such for example as under overload, and also even if both the starter button and the stop or opening button were both inadvertently held depressed, so that even in an emergency if both buttons were operated, nevertheless the switch would open.

Further objects are to provide an electric switch in which stationary contacts are engaged by movable contacts carried by a movable yoke detachably operatively coupled to a starter button, and in which an independent latch mechanism is provided for retaining the yoke in switch closed position, and to provide means which may be actuated either by a closing button to release the latch mechanisms, or which may be operated by over-load devices to release the latch mechanisms, to thereby insure the rising or opening motion of the yoke independently of the starter button or switch closing button.

Further objects are to provide an electric switch which in specific detail may be of the

manual starter type for small polyphase motors in which the starter button is depressed to close the switch and remains depressed under normal conditions, thereby giving an indication that the switch is closed, and to associate with this type of mechanism a trip-free switch mechanism which though normally interlocking with the starter button, nevertheless is detached either by overload conditions or by the operation of a stop button, from the starter button, preferably two independent latch mechanisms being provided one of which retains the yoke in switch closed position, and the other of which secures the operative connection between the starter button and the switch mechanism, so that one of the latches may operate independently of the other, as for instance during the closing motion of the switch, and in which the latch mechanism is so made that both latches may be simultaneously released.

Further objects are to provide a push button switch in which the switch mechanism is closed by means of the switch closing or starter button, in which the switch mechanism is opened either by overload devices or by a stop button, and in which the stop button itself operates as a reset means for resetting the overload devices, whereby it is impossible to close the switch through the agency of the starter button without first resetting the overload devices by depressing the stop or reset button.

Further objects are to provide an electric switch of the push button type which is very compact, which is easy to construct, which is relatively small although accomplishing all of the above enumerated results, and in which a very simple means is provided for detachably retaining the shank carrying the movable contacts in sliding engagement with the yoke, so that these detachable contacts may be removed or renewed as required without removing any screws or other fastening devices of this type.

Further objects are to generally improve the construction of electric switches of the above defined type and to provide a construction which may be easily made, which is

cheap to manufacture, and which is wholly reliable in operation. Other objects of the invention will appear as the description proceeds.

3 An embodiment of the invention is shown in the accompanying drawings, in which:—

Figure 1 is a longitudinal sectional view through the switch, such view corresponding to a section on the line 1—1 of Figure 2.

10 Figure 2 is a plan view of the switch with the cover removed and with parts in section.

Figure 3 is a detailed sectional view approximately on the line 3—3 of Figure 2.

15 Figure 4 is a transverse sectional view on the line 4—4 of Figure 2.

Figure 5 is a view showing a fragment of the yoke, a portion of the shank of the movable contacts, and the retaining clip separated out but indicating their relative interaction.

Referring to the drawings, it will be seen that the switch comprises a body portion 1 of insulation which is carried within a metal casing 2, preferably an insulating sheet 3 being interposed between the rear of the metal casing and the body portion. The metal casing is provided with a metal cover 4 which may be locked in position by sliding the tongue 5 of the cover beneath the tongue 6 of the casing, see Figure 1, and by snapping the other end of the casing into position so that the spring tongue 7 locks the free end of the cover in place, the cover being preferably provided with overhanging flanges 8.

40 The cover is provided with a pair of apertures through which the starting or switch closing button 9 and the opening or stop button 10 pass. If desired, an outwardly projecting flange 13 may surround both buttons.

45 The body portion is provided with pillows or guide posts 14, see Figure 4, upon which an insulating yoke 15 is slidably carried, springs 16 being provided for lifting the yoke to switch open position.

50 The yoke carries the movable contacts and is provided with a plurality of rectangular slots 17, see Figures 2 and 5, which receive the shanks 18 of the movable contacts, which will hereinafter be described. The slots 17 have opposed grooves 17' in the side walls of such slots. The shanks 18 are retained in place by means of retaining clips 19 which slide downwardly into the grooves 17', see Figures 2 and 5, and thereby prevent the shanks 18 from moving outwardly from the rectangular slots.

55 It is also preferable to provide these locking clips 19 with inwardly turned ears 20 which engage within notches 18' formed in the upper ends of the shanks 18, as indicated by the dotted lines transversely of the shanks in Figure 2, and as may be additionally understood from reference to Figure 5. This

70 prevents the inadvertent detachment of the clips from the shanks, and the clips themselves sliding within the opposed grooves formed in the walls of the slots 17 prevent the inadvertent removal of the shanks.

75 Each of the shanks 18 is provided with a contact bridging member or movable contact 21 which bridges the corresponding pair of stationary contacts, the stationary contacts being secured within recessed portions 22 formed in the insulating body portion 1 of the switch.

80 The switch chosen for illustration is of the polyphase type, contacts for three distinct circuits being indicated in Figure 2. In two of these circuits overload devices, such as the well known thermal overload device as indicated at 23 in Figure 2, are provided. The particular type of overload device, of course, may be varied, but, as stated, thermal overload devices have been indicated.

85 These devices, as is well known, are usually provided with a ratchet wheel 24 which engages a spring pressed tongue 25, see Figure 3, such tongue being urged upwardly and into latching position with respect to the wheel 24 by means of the spring 26. Preferably, the lower ends of the latching tongues 25 are pivoted to insulating cylindrical members 27, see Figures 1, 2 and 3. These insulating members 27 are pivotally joined to the tongues 25 by means of the pivot pins 28, as shown most clearly in Figure 3, and such pivot pins ride within slots formed in the guides 29. As indicated in dotted lines in Figure 2 and as shown for one of the insulating members 27 in Figure 3, it will be seen that each insulating member 27 is provided with an offset portion 30, such offset portion 30 being located on opposite sides of the reduced portion 31 of the stem of the opening or stop button 10, see Figure 1.

90 The stem of the switch opening or stop button 10 is provided with a slide 32 spring pressed upwardly by means of the spring 33 and guided upon the stem or post 34. This post 34 and the guiding posts 14, as shown in Figure 4, are each riveted or otherwise secured to a top plate 35 through which the stems from both buttons 9 and 10 pass and by means of which such stems are guided adjacent their upper ends.

95 Referring now to the switch closing or starter button 9, it will be seen that the lower end of the shank is provided with a reduced portion 36 around which the spring 37 for biasing the starter button towards open position is placed.

100 This starter button shank is provided with a notched portion 38, against the lower shoulder of which a pivot pin 39 carried by the yoke normally bears, and against the upper portion of which the upper end of a latch member 40 normally bears, to thereby oper-

atively connect the starter button to the yoke 15, as shown most clearly in Figure 1.

This latch 40 is provided with an integral outwardly projecting portion which is preferably formed of two substantially parallel lever arms 41, each provided with an upwardly approximately centrally located tongue which carries a transverse pin 42.

This pin normally rides on the flat face 10 of a cam member 43 pivotally carried, as indicated at 44, by the top plate 35. The cam member is provided with a cam surface 45 cooperating with a cam surface 46 formed in the shank of the stop button or switch opening button 10, so that when such latter button is depressed, the cam member 43 is rocked in a clockwise direction, engages the pin 42 and trips the latch 40, thereby disconnecting the starter button from the yoke and 15 permitting the yoke to rise so far as the starter button is concerned, although such starter button may be retained inadvertently in depressed position.

An additional latch 47 is loosely pivotally 20 mounted upon the latch 40 by inserting a tongue 48 formed on the latch 47 within a corresponding aperture formed in the latch 40, as shown in Figure 1.

This latch 47 is provided with a bearing portion 48 which is adapted to lock beneath an overhanging member 49 turned downwardly from the top plate 35. It is unseated or detached whenever the latch 40 is disengaged from the shank of the starter or switch closing button 9, as such latch 40 is provided with a tongue 50 which engages the latch 47 and rocks the latch 47 out of engagement with the member 49, thereby permitting the yoke to rise, or in other words, to move to switch 25 open position.

The latches may be tripped by other means than by the stop or switch opening button 10. For example, they are tripped whenever either of the overload devices, such as the 30 thermal overload devices previously described, operate when overload condition obtains. This result is accomplished by the engagement of either or both of the projecting members 30, see Figures 1, 2 and 3, with the lever 41, which latter member is integral with the latch 40. Obviously, therefore, when either member 30 rises due to the operation of the overload device, the lever 41 will be rocked in a counter-clockwise direction, as 35 viewed in Figure 1, and the latch is tripped, thereby allowing the yoke 15 to rise or move outwardly to switch open position.

The switch opening or stop button performs an additional function of resetting 40 either or both of the overload devices. This is accomplished by providing shouldered portions 51 on the shank of the stop button 10 in a position to overhang the projecting members 30, so that such stop button may be depressed to reset the overload devices by press-

ing down one or both of the members 30; depending upon whether one or both of the overload devices has operated, thereby carrying down with such member the corresponding latch 25, see Figure 3, which then engages the ratchet wheel 24, of the thermal overload device which has been chosen as an illustration of an overload device.

It is thus clear that the stop button performs the double function of either independently opening the switch or tripping the latch mechanism as described, or else of resetting the overload devices in the event that either or both of said devices has operated.

The purpose of providing two independent latches 40 and 47 independently spring pressed, as shown in Figure 1, is to permit the rocking of the outer latch 47, as the starter button is depressed independently of any rocking motion of the latch 40, so that the latch 47 may freely move outwardly and then snap between the overhanging member 49 without rocking the latch 40 and thus without interrupting the operative connection between the starter button and the yoke.

It is, of course, within the province of this invention to provide some interlocking mechanism between the cover and the switch parts. For instance, the yoke may be provided with a projecting portion 52, see Figures 2 and 3, which engages a locking bell crank 53 pivotally carried by the casing 2 and adapted to interlock with a hook member 54 carried by the cover 4, as shown in Figure 3.

This bell crank lever is urged towards unlocked position by means of the spring 55 and is moved into locking position whenever the switch is closed, to thereby prevent the opening of the cover until the switch is opened.

It will be seen that an electric switch has been provided which is equipped with a starter button or switch closing button and a stop button or switch opening button, and which is also provided with a yoke carrying movable contacts whose operative connection with the starter button may be interrupted to thus provide a trip-free mechanism to allow the yoke to rise or move outwardly to switch open position whenever the stop button is operated, or whenever either or both of the overload devices operates.

Further, it will be seen that the starter button may be held in closed position and yet the switch may open under any of the above conditions.

It is to be also noted that the stop button or switch opening button has the additional function of resetting the overload devices in the event either or both has operated.

It will be seen further that the device is simple, is easy to construct, and is eminently practical in operation.

Although this invention has been described in considerable detail, it is to be understood

that such description is intended as illustrative rather than limiting, as the invention may be variously embodied and is to be interpreted as claimed.

5 I claim:

1. A push button switch comprising switch mechanism biased towards open position, a push button for closing said switch, locking means for locking said switch mechanism in closed position, a second push button for releasing said locking means, an overload device for tripping said locking means, and means controlled from said second push button for resetting said overload device, where-
10 by when said second push button is depressed said overload device is reset.

2. A push button switch comprising switch mechanism biased towards open position, a push button for closing said switch and nor-
20 mally operatively connected to said switch, locking means for locking said switch in closed position, a second push button for re-
leasing said locking means, an overload device for tripping said locking means, and
25 means controlled from said second push button for resetting said overload device, said overload device interrupting the operative connection between said first mentioned push button and said switch mechanism and said
30 second push button re-establishing said operative connection when said second push button is depressed.

3. A push button switch comprising switch mechanism biased towards open position,
35 locking mechanism for locking said switch mechanism in closed position, a first push button for moving said switch mechanism to closed position, means holding said first push button depressed while said switch mecha-
40 nism is in closed position, an overload de-
vice for releasing said locking mechanism, and a second push button for releasing said locking mechanism.

4. A push button switch comprising switch
45 mechanism biased towards open position, locking mechanism for locking said switch mechanism in closed position, a first push button for moving said switch mechanism to closed position, means holding said first push button depressed while said switch mecha-
50 nism is in closed position, an overload device for releasing said locking mechanism, and a second push button for releasing said locking mechanism, said second push button and said
55 overload device acting independently of each other to release said locking mechanism.

5. A push button switch comprising switch mechanism biased towards open position,
60 locking mechanism for locking said switch mechanism in closed position, a first push button for moving said switch mechanism to closed position, means holding said first push button depressed while said switch mecha-
65 nism is in closed position, an overload de-

vice for releasing said locking mechanism, a second push button for releasing said locking mechanism, said second push button and said overload device acting independently of each other to release said locking mechanism, and means controlled from said second push button for resetting said overload device.

6. A polyphase push button switch comprising switch mechanism biased towards open position, latch means for locking said switch mechanism in closed position, closing means for closing said switch, and a plurality of overload devices for independently tripping said latch means, a release button for releasing said latch means, and means controlled from said release button for re-
70 setting either or both said overload devices.

7. A polyphase push button switch comprising switch mechanism biased towards open position, latch means for locking said switch mechanism in closed position, closing means for closing said switch, releasable operative connecting means between said closing means and said switch mechanism, a plurality of overload devices for independently tripping said latch means, a release button for releasing said latch means, and means controlled from said release button for re-
75 setting either or both said overload devices,
80 the operative connection between said closing means and said switch mechanism being interrupted by the operation of either of said overload devices.

8. A polyphase push button switch comprising switch mechanism biased towards open position, latch means for locking said switch mechanism in closed position, closing means for closing said switch, releasable operative connecting means between said closing means and said switch mechanism, a plurality of overload devices for independently tripping said latch means, a release button for releasing said latch means, and means controlled from said release button for resetting either or both said overload devices, the operative connection between said closing means and said switch mechanism being interrupted by the operation of either of said overload devices,
100 105

9. A push button switch comprising stationary contacts, a yoke, movable contacts carried by said yoke, a spring tending to move said yoke into switch open position, a closing button, latch mechanism detachably connecting said closing button and said yoke, whereby said yoke may be depressed by said closing button, a spring for lifting said closing button, a second latch adapted to lock said yoke in switch closed position, an opening button for releasing said second mentioned latch, and an overload device for releasing both said latches.

10. A push button switch comprising stationary contacts, a yoke, movable contacts
115 120 125 130

- carried by said yoke, a spring tending to move said yoke into switch open position, a closing button, latch mechanism detachably connecting said closing button and said yoke, whereby said yoke may be depressed by said closing button, a spring for lifting said closing button, a second latch adapted to lock said yoke in switch closed position, an opening button for releasing said second mentioned latch, and an overload device for releasing both said latches, said overload device being reset by said opening button. 70
11. A push button switch comprising stationary contacts, a yoke, movable contacts carried by said yoke, a spring tending to move said yoke into switch open position, a closing button, latch mechanism detachably connecting said closing button and said yoke, whereby said yoke may be depressed by said closing button, a second latch adapted to lock said yoke in switch closed position, an opening button for releasing said second mentioned latch, and a plurality of overload devices each independently operative to detach at least one of said latches. 80
12. A push button switch comprising stationary contacts, a yoke, movable contacts carried by said yoke, a spring tending to move said yoke into switch open position, a closing button, latch mechanism detachably connecting said closing button and said yoke, whereby said yoke may be depressed by said closing button, a spring for lifting said closing button, a second latch adapted to lock said yoke in switch closed position, an opening button for releasing said second mentioned latch, and a plurality of overload devices each independently operative to detach at least one of said latches, each of said overload devices being reset by said opening button. 90
13. A push button switch comprising a yoke carrying contacts, stationary contacts cooperating with said first mentioned contacts when said yoke is depressed, a spring urging said yoke to switch open position, a latch restraining said yoke in closed position, a closing button spring urged upwardly and adapted to force said yoke downwardly, a second latch mechanism detachably operatively coupling said button and said yoke, and a stop button for releasing both said latches, whereby said yoke may rise independently of said closing button. 100
14. A push button switch comprising stationary contacts, a yoke provided with movable contacts cooperating with said stationary contacts when said yoke is depressed, a spring urging said yoke upwardly, a closing button independently urged upwardly, latch mechanism for operatively coupling said closing button and said yoke, latch mechanism for locking said yoke in switch closed position, a stop button, cam mechanism operated by said stop button for detaching both latches, 110
15. A push button switch comprising switch mechanism biased towards open position, latch means for locking said switch mechanism in closed position, closing means for closing said switch, an overload device for tripping said latch mechanism, a release button for releasing said latch, and means controlled from said push button for resetting said overload device, the operative connection between said closing means and said switch mechanism being interrupted by the operation of said overload device. 120
16. A push button switch comprising switch mechanism biased towards open position, latch means for locking said switch mechanism in closed position, closing means for closing said switch, an overload device for tripping said latch mechanism, a release button for releasing said latch, and means controlled from said push button for resetting said overload device, the operative connection between said closing means and said switch mechanism being interrupted by the operation of said overload device and remaining interrupted until said release button is operated. 130
17. A switch having stationary contacts, a movable yoke provided with a rectangular slot extending through said yoke and opening laterally thereof, a stem slidably carried within said slot and having movable contacts adjacent one end for cooperation with said stationary contacts and having notches adjacent the other end, said yoke having opposed grooves formed in the walls of said slot, and a fastening clip slidable into said grooves and having ears engaging the notches in said stem, said clip holding said stem in said slot. 140

In testimony whereof, the signatures of the inventors are affixed hereto.

HERMON L. VAN VALKENBURG.

GEORGE W. HOFEM.
